UNITED STATES PATENT OFFICE.

CHESTER P. HALL, OF MAYWOOD, ILLINOIS, ASSIGNOR, BY MESNE ASSIGNMENTS, TO HUBERT NOTEBOOM, OF CHICAGO, ILLINOIS.

AUTOMATIC FIRE-ESCAPE SIGNAL.

1,246,915.

Specification of Letters Patent.

Patented Nov. 20, 1917.

Application filed September 18, 1916. Serial No. 120,837.

To all whom it may concern:

Be it known that I, CHESTER P. HALL, a citizen of the United States, and a resident of the village of Maywood, in the county of Cook and State of Illinois, have invented certain new and useful Improvements in an Automatic Fire-Escape Signal; and I do hereby declare that the following is a full, clear, and exact description of the same, reference being had to the accompanying drawings, and to the numerals of reference marked thereon, which form a part of this specification.

A great many thefts are occasioned in instances where thieves gain entrance into an apartment by means of a fire escape. Access to the fire escape itself is generally readily obtained, in modern constructions, wherein a counter-weighted pivoted ladder or stair section is used which is held in elevated position at the second story of the building by merely engaging a rope or pole over the end of the counter-weighted ladder section and pulling the same downwardly about its pivot support.

This invention relates to an alarm signal adapted to be connected upon a fire escape whereby actuation or downward movement of the movable fire escape section cannot take place without ringing the alarm bell provided. As a consequence unauthorized use of the pivoted counter-weighted ladder section of the fire escape immediately becomes known to persons within hearing.

It is an object of this invention to construct an alarm signal for attachment upon a fire escape without necessitating re-construction of the fire escape members whereby movement of the counter-weighted pivotally mounted lower section of the fire escape ladder is not permitted without sounding an alarm.

It is also an object of this invention to construct an alarm signal for attachment upon a fire escape provided with a pivotally mounted ladder extension whereby actuation of said pivotally mounted ladder extension into downwardly swung position for use sounds the alarm signal.

It is furthermore an important object of this invention to construct a burglar alarm signal for attachment upon fire escapes pro-

vided with a pivotally mounted section which may be swung from the second story landing of the fire escape to the ground beneath, adapted to be connected thereon without changing the fire escape structure, and operating to sound an alarm when the fire escape section is swung downwardly, yet permitting return thereof to elevated position without sounding the alarm or without damage to the alarm signal.

It is finally an object of this invention to construct a thoroughly efficient alarm signal requiring no reconstruction of the fire escape structure nor adjustments of the alarm signal, and operating whenever the fire escape is swung downwardly to sound an alarm thus signaling unauthorized use of the escape.

The invention (in a preferred form) is illustrated in the drawings and hereinafter more fully described.

On the drawings:

Figure 1, is a fragmentary side elevation of a portion of the fire escape equipped with a device embodying the principles of my invention and showing the operation in dotted lines.

Fig. 2, is a sectional view taken on line 2-2, of Fig. 1, with parts omitted.

Fig. 3, is a plan view of the frame plate and associated mechanisms of the device with the gong or bell omitted, showing the means of attachment of the device.

Fig. 4, is a detail section taken on line 4-4, of Fig. 2.

Fig. 5, is a detail view of a modification.

As shown in the drawings:

The reference numeral 1, indicates as a whole a stationary inclined stair or ladder section of a fire escape extending between the second and third floors of the building on which the fire escape is mounted. Said stationary fire escape section 1, is provided with a rigid horizontal pintle shaft 2, and pivotally mounted thereon as shown in Fig.

1, is a downwardly tiltable stair or ladder section 3, which has rigidly connected thereto an arm 4, bearing a counter-weight 5, slightly heavier than the stair or ladder section 3, and as a consequence normally holding the same elevated. Secured upon one end of the pintle shaft 2, is a frame

plate 6, provided with a V-notched clamping extension 7, engaged upon the rigid pintle shaft 2, as clearly shown in Fig. 3, and said frame plate is held rigidly attached in position by a V-notched clamping bar 8, provided with bolts 9, which engage in said extension 7.

A plurality of equidistantly spaced lugs or bosses 10, are formed upon the surface 10 of the frame plate 6, and engaged in each thereof is a stud 11, upon which is pivoted a bell hammer or striker 12. Each of said bell hammers 12, has attached thereto a tension spring 13, which is secured to a 15 fixed point upon the frame plate 6, and normally holds said bell hammer outwardly against a stop 14, one thereof being formed on each of said lugs or bosses 10. Secured centrally in said frame plate 6, is an outwardly projecting stud shaft 15, on the outer end of which is secured a large gong 16, and journaled on the inner end of said shaft 15, is a toothed cam wheel 17, disposed in a position to strike the tail extensions of the bell hammers 12, to actuate the 20 same inwardly against the stress of their springs 13, in successive order, and then to release the same, whereby they may spring outwardly to strike the gong 16.

30 Also journaled upon the shaft 15, between the toothed cam wheel 17, and the surface of the frame plate 6, is a small sheave or pulley 18, having a hub extension upon which is rigidly secured a ratchet wheel 19, disposed adjacent to the toothed cam wheel 17. Pivoted upon the rear surface of the toothed cam wheel 17, is a pawl 20, normally impelled into co-acting driving relation with the ratchet wheel 19, by a spring 21, so that 35 for one direction of rotation of the ratchet wheel 19, the cam wheel 17, is caused to move therewith, but is allowed to remain at rest when said ratchet wheel 19, is rotated in the opposite direction. Coiled around 40 said sheave or pulley 18, is a cable 22, one end of which is attached upon the counter-weight arm 4, and the other end of which is attached upon the tiltable fire escape section 3.

50 In the modified form of device shown in Fig. 5, I have shown one end of the cable 22, connected to a spring 23, attached on the frame plate 6, and with the other end attached as before to the ladder section 3.

55 The operation is as follows:

The normal elevated position of the tiltable fire escape section 3, is shown in Fig. 1. Any unauthorized attempt to pull the 60 same downwardly whereby access may be had to the main fire escape will cause a swinging movement of the section 3, and the arm 4, of the counter-weight 5, about the stationary pivot shaft 2, and consequently a movement of the cable 22, attached there-

to, which is wound around the pulley 18, 65 and which will rotate the same. This rotation of the pulley 18, is, of course, transmitted to the ratchet wheel 19, rigidly associated therewith, and said ratchet wheel 19, will serve to drive the toothed cam wheel 17, through the pawl 20, which is secured 70 upon said cam wheel 17, and is normally in engagement with said ratchet wheel. Rotation of the cam wheel 17, will cause the teeth thereof to strike behind the tail extensions of the respective bell hammers 12, thereby withdrawing the same inwardly 75 against the stress of their respective springs 13, and then suddenly releasing the same to spring outwardly and strike against the 80 gong 16. Of course, it is obvious that any type of springs whatsoever may be utilized to resist movement of the bell hammers 12.

As a consequence, a succession of blows are struck upon the gong 16, and this alarm 85 signifies that the tiltable ladder section 3, of the fire escape is being swung downwardly. It is evident by reference to Fig. 3, that the cam wheel 17, should only be capable of rotation in a counterclockwise direction as the teeth thereof would be jammed 90 against the tail extensions of the bell hammers 12, were rotation in the opposite direction imposed thereupon. Reverse rotation of the cam wheel 17, cannot occur, even 95 though the tiltable fire escape section 3, is swung upwardly again into normal position for the reason that upon the reverse movement of the pulley 18, and ratchet wheel 19, due to the upward swinging of 100 the fire escape section 3, the ratchet wheel 19, tracks beneath the pawl 20, that is, while rotating in clockwise direction as shown in Fig. 4, and does not drive the cam wheel 17.

In the modified form of device illustrated 105 in Fig. 5, I have shown one end of the cable 22, attached to the spring 23, instead of to the counterweight arm 4, so that as a result, when the ladder section 3, is swung downwardly, the spring is tensioned, and again 110 draws the cable back around its sheave 18, when the ladder section is swung upwardly.

I am aware that the details of construction may be varied through a wide range without departing from the principles of 115 this invention, and I therefore do not purpose limiting the patent granted otherwise than necessitated by the prior art.

I claim as my invention:

1. In a fire escape, the combination with 120 a pivoted ladder section, of an audible alarm signal mounted detachably but rigidly upon the pivot of said section, and operative connections between said signal and said pivoted ladder section.

2. In a fire escape, the combination with 125 a pivoted ladder section, of an audible alarm signal mounted detachably but rigidly upon

the pivot of said section and comprising a pulley and mechanism connected with said pulley for sounding the alarm, and a cord attached to said ladder section upon opposite sides of said alarm mechanism and wound around said pulley.

In testimony whereof I have hereunto

subscribed my name in the presence of two subscribing witnesses.

CHESTER P. HALL.
